[57] **CLAIM**

The ornamental design for a combined telescopic holder for note pad and a writing instrument, as shown and described.

DESCRIPTION

FIG. 1 is a top, front and side perspective view of a telescopic note pad holder showing my new design;

FIG. 2 is a side elevational view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a top, front and side perspective thereof, the note pad holder being in an unfolded position.
